APPARATUS FOR MANUFACTURING
CLOSURES

John J. Williams, Wheeling, W. Va., assignor to
Hazel-Atlas Glass Company, Wheeling, W. Va.,
a corporation of West Virginia

Application November 8, 1938, Serial No. 239,566

4 Claims. (Cl. 153—25)

The invention relates to an improved apparatus for manufacturing snap-on closures, particularly such closures in which the skirt is smooth throughout, and without the lugs, or the position of the lugs, being in view.

One of the objects of the invention is to provide a simple and efficient apparatus for manufacturing closures of this type, at high speed.

Various other objects and advantages of the invention will be apparent to those skilled in the art, from the following detailed description, when taken in connection with the accompanying drawings, in which:

Figure 1 is a vertical sectional view of the cap blank.

Figure 2 is a similar view, after the blank skirt has been incurled.

Figure 3 is a vertical sectional view of the apparatus for forming the closure; the die being shown in elevated position.

Figure 4 is a similar view, but with the die in lowered position.

Figure 5 is a horizontal sectional view, taken on line 5—5 of Figure 4.

Figure 6 is a top plan view of the closure.

Figure 7 is a vertical sectional view of the closure, mounted in sealing position on a glass container.

Figure 8 is an enlarged, fragmentary, sectional view of the closure and container, and more clearly showing the relation between the glass finish and one of the incurled lugs on the closure; and

Figure 9 is a view similar to Figure 8, but the section through the closure being taken between the incurled lugs.

Referring to the drawings in more detail, and particularly to Figures 6 to 9, numeral 1 indicates the upper portion of a container, which may be a bottle, jar, tumbler, or other glass container. Numeral 2 refers to a continuous annular glass bead, at the mouth of the container. This bead, which is known as the glass finish, is preferably substantially semi-circular in cross-section, and the locking lugs of the closure are adapted to snap over the bead, in sealing the container, as will clearly appear hereinafter.

The closure, which is referred to generally by the numeral 3, preferably has a flat top 4, and the top may be provided with an annular groove or channel 5.

The depending skirt of the closure is referred to by numeral 6. The lower portion of the skirt is curled inwardly and upwardly, and certain

spaced portions of the incurled bead are flattened outwardly against the skirt, leaving spaced incurled sections 7, which constitute the lugs for snapping over the glass finish 2. It will be noted that the lugs 7 are of considerable length circumferentially, and it will also be noted that the upper end of the incurled lug is spaced from the closure skirt, as indicated by numeral 8. By reason of this space, the resiliency of the lugs is very considerably increased, whereby the closure will fit containers in which the diameter of the finish varies within normal limits, and whereby the removal of the closure is greatly facilitated. In the specific embodiment illustrated, there are three lugs, and each lug has a length which is roughly about one-ninth of the circumference of the closure.

The flattened portions of the incurled bead, between the lugs, are referred to by numeral 9. The internal diameter of the flattened portion of the skirt is greater than the external diameter of the glass finish, so that the flattened portions pass freely over the glass finish. The cross-sectional shape of these flattened portions, best shown in Figure 9, is of material importance. It will be noted, by reference to Figures 8 and 9, that the lower portion of the skirt, at the flattened portions, turns inwardly on exactly the same curvature as the incurled lugs. This curved portion of the skirt is indicated by numeral 10, and from the lower end of this curved portion the flattened portion 9 extends vertically upwardly, with the upper edge portion turned outwardly and downwardly, as indicated by numeral 11.

By reason of the fact that the curvature of the portion 10 at the flattened portions is exactly the same as the curvature at the lugs, it follows that the lower edge of the skirt has the same curvature throughout, and hence neither the lugs nor the position of the lugs are visible from the exterior.

A ring of sealing composition 12 is arranged inside the closure, between the annular groove 5 and the depending skirt 6.

In sealing the containers, the closure is placed loosely thereon, with the incurled lugs 7 resting on the mouth of the containers. In order to seal the container it is only necessary to apply pressure to the top of the closure, whereupon the incurled lugs will snap over the continuous glass bead 2, thereby locking the closure in sealing position. By reason of the space provided between the free end of the incurled lugs and the skirt of the closure, the lugs are more resilient and hence

the closure is more easily applied and removed. Of course the skirt of the closure also springs to some extent, particularly when the closure is applied to maximum diameter containers.

5 The improved apparatus for manufacturing the closure, will now be described, reference being had particularly to Figures 1 to 5.

The blank shown in Figure 1, and referred to by numeral 13, is formed by a cut and draw die; 10 and the edge of the blank skirt is then curled inwardly, as indicated by numeral 14, by means of a curling die. The cut and draw die and the curling die are not illustrated, as they form no part of the present invention.

15 Numeral 15 refers to a supporting plug, and numeral 16 refers to a locating ring slidably mounted on the plug, and normally held in its elevated position by springs 17. When the ring is in its elevated position it assists in properly positioning the closure blank on the supporting plug, and when the expanding die mechanism descends to form the closure it pushes the ring downwardly. The blanks with the incurled bead 14 may be delivered to the supporting plug 15 by 20 hand or by any suitable feed mechanism.

25 Numeral 18 refers to the die holder which is clamped or otherwise secured to the crosshead of a press. Slidably mounted in the die holder is an ejector pad 19, which is normally maintained in elevated position relative to the die holder, by a coil spring 20.

A centering ring 21 is mounted on the lower end of the die holder, and this ring is preferably beveled as indicated by numeral 22. Above the 30 beveled portion the ring is cylindrical to conform to the cylindrical blank skirt. Above the cylindrical portion the centering ring curves inwardly a short distance, as indicated by numeral 23, and this curvature is the same as the curvature of the incurled bead 14. This curved portion 35 23 of the ring is in contact with the incurled bead, when the expanding die comes into action, and thus the exterior curvature of the lower edge of the closure is maintained uniform throughout.

40 45 The expanding die segments, three in number, are referred to by numeral 24, and these segments are mounted for sliding lateral movement, between the holder 18 and ring 21; the segments being maintained in proper circumferential position, and normally urged inward, by spring 25.

50 The segments 24 have conical surfaces cooperating with conical ejector pad 12, so that when the segments move downward relative to the pad, they are forced outwardly to pinch or flatten the incurled bead 14 at the desired points. The outer face of each expanding die segment has a cylindrical portion 26 which comes into contact with the incurled bead 14 in the flattening 55 60 operation. And the outer face of each of these segments also has cut-away portions 27, and these portions are cut back far enough to prevent contact between them and the incurled bead, so that the bead retains its original form at these points. These portions of the incurled bead which retain their original shape, constitute the locking lugs 7 of the closure.

65 In operation, blanks with the incurled bead 14 are delivered to the supporting plug 15 by any 70 desired means, and are properly positioned thereon by the locating ring 16. The expanding die holder now descends bringing the pad 19 into contact with the bottom of the closure blank and firmly holding it in position during the 75 forming operation.

In this downward movement of the die holder, the centering ring 21 engages the locating ring 16 and moves it downwardly, while the cylindrical portion of the centering ring passes over the blank skirt.

5 After the pad 19 contacts with the bottom of the blank, it cannot move further downward, but the die holder and associated parts continue their downward movement. This slight further downward movement brings the curved portion 10 23 of the centering ring into contact with the exterior curved edge of the bead 14, preventing any deformation of the exterior curvature of the bead; and at the same time the expanding die segments are moved outwardly, thereby flattening the bead 14 where the cylindrical surfaces 26 of the segments contact with the bead, to form the flattened portions 9 of the closure. The cut-out portions 27 of the expanding die segments do not contact with the incurled bead, 20 and these undeformed portions of the bead constitute the locking lugs 7 of the closure. Thus the closure is completed in one stroke of the die.

The die holder and associated parts now move upwardly, carrying the completed closure in the 25 centering ring. As the die holder approaches its upper limit of travel the stem of the ejector pad strikes an arm (not shown), which prevents further upward movement of the pad. The other parts continue their upward movement, causing 30 a relative downward movement of the ejector pad to forcibly eject the completed closure. The closures fall by gravity, or may be blown by compressed air, into a container suitably placed to receive them.

35 As previously mentioned herein, the snap-on closure disclosed herein possesses numerous advantages over prior closures of this type. It presents an unusually attractive appearance, by reason of the fact that the skirt is smooth 40 throughout, and with neither the lugs nor the position of the lugs being in view. Also, the closure is very strong, produces an efficient seal, and may be easily removed when the container is to be opened. Further, the construction of 45 the closure is such that it may be manufactured at a high rate of speed by the apparatus disclosed herein, requiring only a single stroke of a die to complete the closure, from a blank having an incurled bead.

50 55 No claim is made herein to the closure; such claims being made in my divisional application Serial Number 275,299, filed May 23, 1939.

Having fully described the invention, what I claim is:

1. Apparatus for forming metallic closures with snap-on lugs, including a plug to receive a blank having a skirt with an incurled bead, a die holder, a ring carried by the die holder, said ring having a cylindrical portion corresponding with the blank skirt, and also having an incurved portion above the cylindrical portion and corresponding with the cross-sectional curvature of the blank where the bead joins the skirt, a plurality of expanding die segments carried by the die holder, the die segments having smooth wide external operating faces curved to substantially the curvature of the closure skirt, said operating faces being circumferentially spaced apart where the lugs are to be positioned whereby the incurled bead remains undeformed at said spaced points, and means for moving the segments outwardly to flatten circumferentially spaced portions of the incurled bead.

2. Apparatus for forming metallic closures with 75

5 snap-on lugs, including a plug to receive a blank having a skirt with an incurled bead, a vertically movable locating ring slidably mounted on said plug, a die holder, a centering ring carried by the die holder, said centering ring having a cylindrical portion corresponding with the blank skirt, and also having an incurled portion above the cylindrical portion and corresponding with the cross-sectional curvature of the blank where 10 the bead joins the skirt, a plurality of expanding die segments carried by the die holder, the die segments having smooth wide external operating faces curved to substantially the curvature of the closure skirt, said operating faces being circumferentially spaced apart where the lugs are 15 to be positioned whereby the incurled bead remains undeformed at said spaced points, said segments having inner faces cooperating with the conical ejector pad, springs maintaining the segments in operative relation with the conical 10 ejector pad, and said segments when moved outwardly engaging and flattening circumferentially spaced portions of the incurled bead.

15 3. Apparatus for forming metallic closures with snap-on lugs, including a plug to receive a blank having a skirt with an incurled bead, a vertically 20 movable locating ring slidably mounted on said plug, a die holder, a centering ring carried by the die holder, said centering ring upon downward movement adapted to engage and move downward the locating ring, said centering ring 25 having a cylindrical portion corresponding with the blank skirt, a conical ejector pad carried by the die holder and adapted to engage the blank on the plug, a plurality of expanding die 30 segments carried by the die holder, the die segments having smooth wide external operating faces curved to substantially the curvature of the closure skirt, said operating faces being circumferentially spaced apart where the lugs are 25 to be positioned whereby the incurled bead remains undeformed at said spaced points, and an injector pad, said pad having downwardly flared sides for moving the segments outwardly to engage and flatten circumferentially spaced 30 portions of the incurled bead.

4. Apparatus for forming metallic closures with snap-on lugs, including a plug to receive a blank 15 having a skirt with an incurled bead, a die holder, means carried by the holder for engaging and maintaining the cross-sectional curvature of the blank where the bead joins the skirt, throughout the circumference of the blank, expanding die segments carried by the die holder, the die segments having smooth wide external operating faces curved to substantially the curvature of the closure skirt, said operating faces being circumferentially spaced apart where the lugs are 20 to be positioned whereby the incurled bead remains undeformed at said spaced points, said segments having inner faces cooperating with the conical ejector pad, springs maintaining the segments in operative relation with the conical 10 ejector pad, and said segments when moved outwardly engaging and flattening circumferentially spaced portions of the incurled bead.

JOHN J. WILLIAMS.
